(57) **CLAIM**

The ornamental design for a vehicle body exterior, as shown and described.

DESCRIPTION

FIG. 1 is a top front perspective view of a vehicle body exterior, showing my new design;

FIG. 2 is a right-side elevation view thereof, the left-side elevation view being a mirror image thereof;

FIG. 3 is a top plan view thereof;

FIG. 4 is a front elevation view thereof; and,

FIG. 5 is a rear elevation view thereof.

The evenly spaced broken lines shown in the drawings depict portions of the vehicle body exterior that form no part of the claimed design.

The contour lines in the drawings represent contoured surfaces of the claimed design and do not illustrate material, surface ornamentation, or surface decoration.
